UNITED STATES PATENT OFFICE

PETER W. LACINA, DECEASED, LATE OF LENNEY, SASKATCHEWAN, CANADA, BY MERTINA LACINA, ADMINISTRATRIX, OF LENNEY, SASKATCHEWAN, CANADA

FLYING MACHINE

Application filed March 27, 1929. Serial No. 350,349.

The present invention relates to a flying machine and has for its prime object to provide a structure of this nature capable of great maneuver ability and easy of control.

5 Another very important object of the invention resides in the provision of a flying machine of this nature which is comparatively simple in its construction, strong and durable, thoroughly efficient and reliable in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

20 Figure 1 is a top plan view of the flying machine embodying the features of the invention,

Figure 2 is an enlarged detail sectional view taken substantially horizontally 25 through one of the propellers,

Figure 3 is a perspective view of one of the blades of the propeller,

Figure 4 is a detail section through the connection of one of the blades with the 30 gears in the gear casing,

Figure 5 is an elevation of one of the gear casings, and

Figure 6 is a view thereof with the cover plate removed.

35 Referring to the drawing in detail it will be seen that the numeral 5 denotes a stream line fuselage to the sides of the tail of which extend wing structures 6 with openings 7 therein and in these openings 7 are rockably 40 mounted ailerons 8 controlled by suitable means 9 from the seat 10 in the cockpit of the fuselage. To the sides of the fuselage 5 adjacent the cockpit there extends frames 11 which are braced from the nose of the 45 fuselage by staves 12.

Shafts 14 are journaled in the ends of the frames 11 and through the sides of the fuselage 5. A plurality of spokes 15 radiate from a hub 16 on the end of each shaft 14 and these spokes are braced by braces 17 ex-

tending from intermediate portions thereof inwardly to a second hub 18 anchored on the shaft 14.

An annular gear casing 19 is keyed as at 20 on the shaft 14 adjacent the fuselage and 55 has a cover plate 21. A plurality of blades 22 have outer trunnions 23 journaled in the end of the spokes 15 and inner trunnions 24 journaled in the casing 19 and terminating in squared ends 25 on which are disposed 60 gears 26 meshing with gears 27 journaled in the casing.

These gears 27 are disposed in an annular series within the annular series of gears 26. A gear 28 meshes with the gears 27 and is 65 fixed or keyed on a sleeve 29 rockable in the fuselage and about the shaft 14 and having a control crank 30 on the inner end thereof.

Obviously by rocking the crank 30, through the gears 28, 27 and 26 the blades 70 may be changed so as to vary the speed position thereof depending upon whether the propeller is to lift, move the machine forward, or both as will be quite apparent from an inspection of Figure 6.

75 A suitable prime mover such as an internal combustion engine 32 is disposed in the fuselage and rotates the gears 34 in mesh with the gears 33 on the inner ends of the shafts 14.

80 From the above detailed description it will be seen there has been devised a flying machine with propeller structures on the sides thereof wherein the propellers may be articulated about their own axes so that when moved in an orbit about the shaft 14 they will function to control the aeroplane in the desired maneuver to be made.

85 The structure is exceedingly compact and convenient in its arrangement of parts and possesses simplicity and easy to control.

90 It is thought that the construction, operation, utility and advantages of the invention will be quite apparent. It is desired to point out that a universal joint 42 is disposed between each trunnion 24 and the respective gear 26 associated therewith because it is desirable that the blades of each propeller diverge outwardly from each other.

95 This universal joint 42 is housed to the 100

casing 43 slotted as at 44 to accommodate trunnions 24.

The present embodiment of the invention has been disclosed in considerable detail merely for the purposes of exemplification since in actual practice it attains the features of advantage enumerated as desirable in the statement of the invention and the above description.

10 It will be apparent that changes in the details of construction, and in the combination and arrangements of parts may be resorted to without departing from the spirit or scope of the invention as hereinafter 15 claimed or sacrificing any of its advantages.

Having thus described the invention, what is claimed as new is:

1. A flying machine of the class described including a fuselage, frames extending from 20 the sides of the fuselage, shafts journaled in the fuselage and the frame, spokes radiating from the outer end of the shaft, blades journaled in the ends of the spokes, means for supporting the inner ends of the propellers 25 about the shaft, a casing keyed on said shaft at the inner end thereof, gearing in the casing, means for operating the gearing, and means for operatively connecting the inner ends of the blades with the gearing.

30 2. A flying machine of the class described including a fuselage, frames extending from the sides of the fuselage, shafts journaled in the fuselage and the frame, spokes radiating from the outer end of the 35 shaft, blades journaled in the ends of the spokes, means for supporting the inner ends of the propellers about the shaft, a casing keyed on said shaft at the inner end thereof, gearing in the casing, means for operating 40 the gearing, and means for operatively connecting the inner ends of the blades with the 45 gearing, said blades diverging outwardly from each other and said means including universal joints.

45 3. A propeller unit for a flying machine comprising a shaft, a plurality of spokes radiating from adjacent one end of the shaft, a casing adjacent the other end of the shaft, a sleeve rockable in the casing about the 50 shaft, a gear on the sleeve, a plurality of gears journaled in the casing and operatively connected with the first mentioned gears, a plurality of blades rockable in the ends of the spokes and operatively connected with 55 the second mentioned gears.

60 4. A propeller unit for a flying machine comprising a shaft, a plurality of spokes radiating from adjacent one end of the shaft, a casing adjacent the other end of the shaft, a sleeve rockable in the casing about the 65 shaft, a gear on the sleeve, a plurality of gears journaled in the casing and operatively connected with the first mentioned gears, a plurality of blades rockable in the ends of the spokes and operatively connected with 70 75 80 85 90 95 100 105 110 115 120 125 130

the second mentioned gears, universal joints operatively connecting the inner ends of the blades with the second mentioned gears.

5. A propeller unit for a flying machine comprising a shaft, a plurality of spokes radiating from adjacent one end of the shaft, a casing adjacent the other end of the shaft, a sleeve rockable in the casing about the shaft, a gear on the sleeve, a plurality of gears journaled in the casing and operatively connected with the first mentioned gears, a plurality of blades rockable in the ends of the spokes and operatively connected with the second mentioned gears, universal joints operatively connecting the inner ends of the blades with the second mentioned gears, a crank on the sleeve for rocking the same.

In testimony whereof, I affix my signature.
MERTINA LACINA,
Administratrix of the Estate of Peter W. Lacina, Deceased.
